AMPLIFIER TUBE

Popko Reinder Dyksterhuis, Eindhoven, Netherlands, assignor to Radio Corporation of America, a corporation of Delaware

Application August 30, 1930, Serial No. 478,833
In the Netherlands September 30, 1929

8 Claims. (Cl. 179—171)

The present invention relates to amplifiers, and more particularly to improvements in, or relating to, circuit arrangements for amplifying tubes with so-called parallel feeding.

5 The so-called parallel feeding of amplifying valves has the advantage that the core of the amplifier transformers is free of direct current magnetization, owing to which one of the most important causes of distortion is suppressed, and 10 the transformer may be given much smaller dimensions. However, with the usual circuit arrangements these advantages are obtained at the cost of the amplification and economy, for in order to keep the same amplification and to leave 15 unaltered the linear course of the characteristic curve of the coupling transformer, choke-coil or auto-transformer, it would be necessary to supply the anode current through an infinitely high alternating current resistance, while the alternating 20 current must be supplied to the coupling element through a condenser of infinitely high capacity.

As a rule, a compromise is made and for the sake of economy, a portion of the attainable amplification is given up. One is notwithstanding compelled to employ choke-coils having a self-inductance which is a few times as large as that of the primary winding of the coupling transformer, while, in addition, the value of the capacity connected in series is very high, said value 30 being as a rule of the order of magnitude of two microfarads.

The present invention has for its main object to provide means permitting better results with considerably smaller values of inductance and 35 capacity of the said elements. This affords the double advantage of the working being improved and the manufacture being made cheaper.

These advantages are obtained by judiciously 40 dimensioning the parallel inductance and the series capacity. Thus, according to the invention, the self-induction of the choke-coil is chosen so as to be from 1 to 2 times as large as the self-induction of the primary winding of the coupling 45 transformer, and besides, the damping of the circuit formed by the internal resistance of the valve, the series condenser and the primary winding of the transformer, is made equal to the angular frequency of the natural oscillation of 50 the circuit constituted by the primary winding, and the series-condenser while neglecting the loss resistance. It is evident that it does not matter which of the various elements should be considered to be given provided that the said relation is satisfied. The frequency of the said

natural oscillation should conveniently be so chosen as to be substantially equal to 50 to 100. From this point on, the frequency characteristic curve has a substantially flat course and not until the region of the high tones does the curve deviate, and does it fall more or less abruptly according to circumstances. 60

In the high regions of the audible frequencies the characteristic curve can be straightened by connecting an inductance coil between the series condenser and the primary winding of the transformer, and by connecting a condenser in parallel to the said winding, the self-inductance and the capacity of these elements being so chosen that the natural frequency of the circuit constituted by these elements is located in the high portion of the sound spectrum while the damping of the circuit formed by these elements in series with the internal resistance of the corresponding valve, (consequently, practically the internal resistance of the valve divided by the impedance of the inductance at the said frequency) is smaller than unity. 70

At this choice of the various magnitudes an amplification characteristic curve is obtained 80 which from 50 to 100 cycles up to 9 to 10,000 cycles is substantially straight, and abruptly falls downwards both on the low and on the high side. If an additional condenser is connected in parallel to the anode-filament circuit of the valve, 85 the characteristic curve will fall on the high side still more abruptly, and, besides, feed back effects, which at the high frequencies may be troublesome, will be suppressed.

The novel features which I believe to be characteristic of my invention are set forth in particularity in the appended claims, the invention itself, however, as to both its organization and method of operation will best be understood by reference to the following description taken in 95 connection with the drawing in which I have indicated diagrammatically several circuit organizations whereby my invention may be carried into effect.

In Fig. 1, R_1 is a triode, L_s a choke coil, C_1 a 100 condenser, L_1 the primary winding of a transformer whose secondary winding L_2 is included in the grid circuit of the next triode conventionally shown as a utilization means, L_s is connected on one side to the anode of the valve 1, and on 105 the other side to the positive terminal of a source of anode current, the source not being shown. C_1 and L_1 are connected in series between the anode and the cathode of the valve 1, the internal resistance of this valve being assumed to be R_1 . 110

The reference characters aforementioned are used to indicate electrical values. According to the invention, C_1 , L_1 and L_3 are so dimensioned that:

$$(1) L_3 = 1 \text{ to } 2 L_1$$

$$(2) \frac{R_1}{L_1} = \frac{1}{V L_1 C_1} = W_1 \text{ (The angular frequency)}$$

At a given value of R_1 and consequently with a given value it is possible to obtain any desired value of W_1 by a suitable choice of the value of L_1 . For the reproduction of speech and music it is usually sufficient to take W_1 equal to about 1000 (pitch of tone)

$$15 \quad \frac{1000}{2\pi} \quad (2\pi)$$

and at any rate it is not necessary to take W_1 smaller than 300.

The dimensioning indicated renders it possible to take the ratio of transformation of the coupling transformer considerably larger than with the transformers hitherto known. Whereas, up to the present, one was obliged to restrict oneself to a ratio of 1:3, the invention allows, without any objection, to go as high as 1:10 with the usual triodes having an internal resistance of the order of magnitude of 10,000 ohms. The above described circuit arrangement gives particularly favorable results in the low portion of the frequency range to be transmitted.

For transmitting, in addition, the high portion with substantially the same strength use may be made of the circuit arrangement shown in Fig. 2 in which between the series condenser and the primary winding is connected a filter element $L_3 C_3$, to which may be added, if desired, a condenser C_4 .

Fig. 3 represents the substitution diagram of the circuit arrangement according to Fig. 2. It appears from Fig. 3 that the whole of it may be taken as a system of two coupled circuits, namely: R_1 , C_1 ; L_3 , C_3 ; and $(1-k^2) L_1$, R_2^1 , C_2^1 , in which $(1-k^2) L_1$ is the leakage inductance of the transformer, and R_2^1 and C_2^1 represent the secondary resistance and the self-capacity plus the load capacity of the transformer transformed to the primary side. L_1 is the primary inductance, the impedance of which may be considered in this case as being practically infinite. The resonance (leakage resonance) of the circuit $(1-k^2) L_1$, C_2^1 is practically located at about 5000 cycles. L_3 and C_3 are so chosen that

$$\frac{1}{V L_3 C_3} = W_3$$

55 is of the order of magnitude of 40,000 (about 7000 cycles).

Furthermore, L_3 is so chosen that:

$$60 \quad \frac{R_1}{W_3 L_3} < 1$$

The curve C of Figure 4 represents a frequency characteristic curve of the system of Figure 2, in which the various magnitudes had the following values.

$$R_1 = 10^4 \text{ ohms}$$

$$L_3 = 12 \text{ H}$$

$$L_1 = 10 \text{ H}$$

$$C_1 = 0.1 \mu \text{F}$$

$$L_2 = 1000 \text{ H}$$

$$1-k^2 = 0.015$$

$$C_2^1 = 0.005 \mu \text{F}$$

$$R_2^1 = 10^3 \text{ ohms}$$

$$C_3 = C_4 = 0.002 \mu \text{F}$$

$$L_3 = 0.3 \text{ H}$$

Without the addition of the filter element the characteristic curve would fall abruptly beyond the leakage resonance frequency. By adding the filter element whose natural frequency is slightly higher than that of the leakage resonance, the region in which the curve is flat is considerably broadened while the descent begins at about 9 to 10,000 cycles. By adding the condenser C_4 the descent at the high frequencies is still more abrupt.

At a given value of R_1 and consequently with a given value it is possible to obtain any desired value of W_1 by a suitable choice of the value of L_1 . For the reproduction of speech and music it is usually sufficient to take W_1 equal to about 1000 (pitch of tone)

15 and at any rate it is not necessary to take W_1 smaller than 300.

The dimensioning indicated renders it possible to take the ratio of transformation of the coupling transformer considerably larger than with the transformers hitherto known. Whereas, up to the present, one was obliged to restrict oneself to a ratio of 1:3, the invention allows, without any objection, to go as high as 1:10 with the usual triodes having an internal resistance of the order of magnitude of 10,000 ohms. The above described circuit arrangement gives particularly favorable results in the low portion of the frequency range to be transmitted.

What I claim is:

1. In an amplifier, the combination of an electron discharge tube provided with an anode circuit, an inductance connected in said circuit, a condenser, and a transformer provided with a primary circuit connected to said anode circuit through said condenser, the self-inductance of the inductance having a value from one to two 100 times as large as the self-inductance of the said primary circuit, and the ratio of the internal impedance of the tube to the self-inductance of the primary circuit being substantially equal to the value of the natural angular frequency of the path 110 including the said condenser and primary circuit.

2. In an amplifier, the combination of an electron discharge tube provided with an anode circuit, an inductance connected in said circuit, a condenser, and a transformer provided with a 120 primary circuit connected to said anode circuit through said condenser, the self-inductance of the inductance having a value from one to two 130 times as large as the self-inductance of the said primary circuit, and the ratio of the internal impedance of the tube to the self-inductance of the primary circuit being substantially equal to the value of the natural angular frequency of the path 140 including the said condenser and primary circuit, said natural frequency being between 50 150 to 100.

3. In an amplifier, the combination of an electron discharge tube provided with an anode circuit, an inductance connected in said circuit, a condenser, and a transformer provided with a 160 primary circuit connected to said anode circuit through said condenser, the self-inductance of the inductance having a value from one to two 170 times as large as the self-inductance of the said primary circuit, and the ratio of the internal impedance of the tube to the self-inductance of the primary circuit being substantially equal to the value of the natural angular frequency of the path 180 including the said condenser and primary circuit, and a load circuit connected in the secondary circuit of said transformer.

4. In an amplifier, the combination of an electron discharge tube provided with an anode circuit, an inductance connected in said circuit, a condenser, and a transformer provided with a 190 primary circuit connected to said anode circuit through said condenser, the self-inductance of the inductance having a value from one to two 200 times as large as the self-inductance of the said primary circuit, and the ratio of the internal impedance of the tube to the self-inductance of the primary circuit being substantially equal to the value of the natural angular frequency of the path 210 including the said condenser and primary circuit, and the ratio of the internal impedance of the tube to the self-inductance of the primary circuit being substantially equal to the value of the natural angular frequency of the path 220 including the said condenser and primary circuit, and a load circuit connected in the secondary circuit of said transformer.

- impedance of the tube to the self-inductance of the primary circuit being substantially equal to the value of the natural angular frequency of the path including the said condenser and primary circuit, an inductance coil between the condenser and primary circuit, and a condenser connected in parallel with the latter, the coil and parallel condenser being so chosen as to be resonant to a frequency at the high frequency end of the amplifier frequency range. 80
- 5 5. In an amplifier, the combination of an electron discharge tube provided with an anode circuit, an inductance connected in said circuit, a condenser, and a transformer provided with a primary circuit connected to said anode circuit through said condenser, the self-inductance of the inductance having a value from one to two times as large as the self-inductance of the said primary circuit, and the ratio of the internal impedance of the tube to the self-inductance of the primary circuit being substantially equal to the value of the natural angular frequency of the path including the said condenser and primary circuit, a network, resonant to a frequency at 90
- 15 the high frequency end of the amplifier frequency range, between the condenser and primary circuit, and an additional condenser connected in parallel with the anode and cathode of said tube. 95
- 20 6. In an amplifier, the combination with a tube provided with an anode circuit, a choke coil connected in the circuit, a source of anode potential connected to the coil, a capacity, an inductive coupling means connected to said anode circuit 100
- 25 30 35 40 45 50 55 60 65 70 75
5. In an amplifier, the combination with a tube provided with an anode circuit, an inductance coil connected in the circuit, a capacity, an inductive coupling means connected to said anode circuit through said capacity, said coupling means being resonant to a frequency at the low frequency end of the amplifier frequency range, and a network connected between the capacity and coupling means, the network being resonant to a frequency at the high frequency end of the amplifier frequency range. 85
7. In an amplifier, the combination with a tube provided with an anode circuit, an inductance coil connected in the circuit, a capacity, an inductive coupling means connected to said anode circuit through said capacity, said coupling means being resonant to a frequency at the low frequency end of the amplifier frequency range, and a network connected between the capacity and coupling means, the network being resonant to a frequency at the high frequency end of the amplifier frequency range, said network comprising an inductance in series with the capacity and coupling means and a condenser in shunt with the coupling means. 90
8. In an amplifier, the combination with a tube provided with an anode circuit, a choke coil connected in the circuit, an anode potential source connected to the coil, a capacity, an inductive coupling means connected to said anode circuit through said capacity, a network connected between the capacity and coupling means, the network being resonant to a frequency at the high frequency end of the amplifier frequency range, 105 and a condenser connected in shunt with the tube, between the anode and cathode thereof, to secure a sharp cut-off at said high frequency end. 110
